RAZOR BLADE

Harold D. Davis, New York, N. Y.

Application April 27, 1954, Serial No. 30,203

Term of patent 14 years

(Cl. D22—3)

To all whom it may concern:

Be it known that I, Harold D. Davis, a citizen of the United States of America and a resident of New York, county of Kings, and State of New York, have invented a new, original, and ornamental Design for a Razor Blade, of which the following is a specification, reference being had to the accompanying drawing, forming part thereof.

Fig. 1 is a plan view of a razor blade embodying my new design; and

Fig. 2 is a top edge view thereof.

I claim:

The ornamental design for a razor blade, substantially as shown.
